UNITED STATES PATENT OFFICE.

EDWARD L. DAVIS, OF SCHENECTADY, NEW YORK.

STEAM-HEATING APPARATUS.

1,212,611.

Specification of Letters Patent. Patented Jan. 16, 1917.

Application filed September 14, 1914. Serial No. 861,574.

To all whom it may concern:

Be it known that I, EDWARD L. DAVIS, a citizen of the United States, residing at Schenectady, in the county of Schenectady and State of New York, have invented certain new and useful Improvements in Steam-Heating Apparatus, of which the following is a specification.

The object of the invention is to provide 10 a steam heating system by which radiators of the usual type may be supplied with steam in any graduations within the range of the supply, and the water of condensation returned to its source, by a single pipe.

15 It is an important object to enable the location of a controlling valve at the top of the radiator, whereby steam may be admitted at the upper part of the radiator or coil while the water of condensation is conducted 20 from the lower part into the same pipe from which steam is derived without liability of steam entering through the outlet.

It is a further object to effect a simplification of the structural parts required to 25 enable the modulation of heat radiation in radiators, and to effect a saving in material and labor over prior systems and construction and to present a compact embodiment of the invention whereby the results desired 30 may be attained.

It is to be particularly noted that my invention effects a saving in the cost of supply valves, for the reason that as they have but the one function of supplying steam to the 35 radiator, a much smaller sized valve may be employed than is required in the conventional one-pipe steam heating system.

In the customary installation of one pipe steam heating systems the supply valve 40 must be placed at the base of the radiator for it not only furnishes the radiator with steam but it also receives and leads away the water of condensation therefrom, for this reason a supply valve when so disposed 45 can not be controlled nor regulated to furnish a lesser amount of steam than its maximum opening affords as it must be either turned full open or tightly closed and the radiator to which it is attached is either entirely heated or cold. My invention overcomes these difficulties.

Additional objects, advantages and features of invention will appear from the construction, arrangement and combination of 55 parts hereinafter set forth and illustrated in the drawings, where,

Figure 1 is a side elevation of a radiator and immediate connections constituting one of the possible embodiments of my invention, Fig. 2 is a similar view illustrating an 60 arrangement suitable for certain types of radiators, Fig. 3 is a detail section of the outlet structure, Fig. 4 is an elevation of the valve plug at the outlet, Fig. 5 is a detail of a modified construction of fitting for controlling movement of fluids from the outlet, 65 particularly suitable for use as shown in Fig. 2, but adaptable readily to use with the arrangement shown in Fig. 1, as will be understood from the particular description 70 following.

There is illustrated a radiator 10 of usual construction to which steam is supplied from any suitable source through a pipe 11 of usual size for the capacity of the radiator. 75 The upper boss 12 of one end column is tapped and fitted with an inlet valve 13, of any usual construction, in the present case, a graduated hand controlled supply valve being formally indicated from which the 80 supply pipe 14 extends vertically downward. This pipe may be smaller than the one 11, although this is not essential, and is connected to the pipe 11 by the T 15, from the center of which connection is made to 85 the outlet opening 16, which may be the standard tapping in the lower boss 17 of the column 18 of the radiator to which the inlet valve 13 is connected. The connection between the outlet and the T 15 is formed by a 90 small nipple 19 which is centered eccentrically of the outlet opening, and closely adjacent the bottom thereof. This nipple would ordinarily require a bushing, the function of which is served by a cored 95 externally threaded cylindrical casting 20 with which the nipple 19 is engaged, and which in addition forms a casing by which a controlling device may be accommodated at the same time in the outlet opening. The 100 casting 20 is closed at its outer end by a head plate 21 tapped as at 22 to receive the outlet nipple 19, and in line with this opening a larger inlet opening 23 is formed in a thinner head 24 closing the inner end of the 105 casting. The opening 23 is smoothly finished and slightly tapered so as to receive the circular plate 25 to be secured by a tight push fit, and having a stop flange 26 to limit its engagement in the casing. An outlet 110 port 27 is formed in this plate 25 concentric with the tap opening 22 at the outer side

of the casing. Pivoted between ears 28 on the plate 25 located above the port there is an arm 29, offset to lie spaced from and parallel to the plate 25, upon which arm, 5 next to the plate, there is carried a splayed disk valve 30 arranged to seat snugly at the inner end of the port 27. The plate 25 and valve are preferably of brass or other comparatively non-corrosive metal, while the 10 casting 20 may be of iron.

The parts being assembled as described, it will be apparent that upon admission of steam to the pipe 11, it is prevented from entering at the bottom of the radiator by the 15 valve 30 seating over the port 27, and it can only gain access to the radiator through the valve 13 when open. By proper adjustment of the valve 13 any desired flow of steam may be obtained, without liability of impedance, or irregularity of action, as all 20 water of condensation falls away and drains through the port 27, the valve 30 being so hung as to yield to slight pressure from within. The radiator may thus be wholly 25 or partially heated to the degree desired.

Where the radiator is of considerable length, principles well understood in the art may dictate that the outlet should be located at the opposite end from the inlet. 30 In this case it is desirable to utilize a T valve as shown in Figs. 2 and 5. The T casting 31 is made with a proper seat 32 at the inner end of the center connection, and by means of a pin 33 engaged through the 35 casting from the outside, the valve arm 34 is pivoted so that the valve 35 thereon may engage in the seat. The T 31 is connected between the pipes 11 and 14 and drain connections 36 made between the outlet and the 40 center of the T. My device as shown in Fig. 3 may, however be utilized in the outlet 37, and simple drain connections made from the opening 22 to the pipe 11.

It is apparent that my invention will be 45 equally applicable to use in connection with a steam supply above or below atmospheric pressure.

It is to be noted that the invention will 50 separate the steam from the returning water of condensation upon admission to the radiator so that the heating vehicle will be drier than is possible with an inlet valve placed at the bottom of the radiator as in the ordinary one-pipe system. Accumulation of 55 water in radiators, either in the form of excessive moisture in the steam or by condensation after closing of the supply valve, is obviated. There will consequently be less 60 irregularity in the operation of the system. For instance, with the ordinary installation,

as the radiator may only be heated to the maximum when the supply valve is opened, when this valve is closed, a large quantity of water will accumulate. When next it is opened, the returning water will chill a 65 large section of the supply line, causing a lowering of pressure in the entire system, with a possible deficiency in heat at other points, as well as delayed heating of the radiator from which the water escapes. 70 When a number of radiators have thus accumulated water, the level of water in the boiler from which the steam is derived may be replenished, and upon opening of the valves on the radiators, the boiler may be 75 flooded, or at least such excess accumulated as to materially affect its efficiency.

The device secures all the advantages of the familiar one-pipe systems, with additional advantages. However, it is not limited to such uses and systems, but will be found applicable to other situations and systems as well. It is obvious, too, that other embodiments of the invention are possible within the scope of the claims, in addition 85 to that herein shown and described.

What is claimed is:

1. In steam heating apparatus, a bushing and valve casing to engage within the outlet of radiators comprising a cylindrical exteriorly threaded hollow casting having integral closing plates at each end, one having a tapped opening for pipe connection, the other having an inlet port formed therein to receive the return from a radiator, and a valve within the casing movably mounted for engagement over the port yieldably for egress of water.

2. A device for the purpose described comprising a bushing and casing consisting of 100 an exteriorly threaded hollow cylindrical element having head portions thereacross at each end, and constructed to be screwed into the bottom of a radiator unit, one of the heads having an interior threaded opening 105 therethrough coincident at one side with the inner surface of the cylindrical portion mentioned, the other head having an opposed opening therein, a ported element fixed in the last named opening, and a check 110 valve mounted on the inner side thereof, to close the port in said ported element, and yieldable to pressure therethrough.

In testimony whereof I affix my signature in presence of two witnesses.

EDWARD L. DAVIS.
